A. WAGNER

AUXILIARY AIR VALVE FOR INTERNAL COMBUSTION ENGINES

Filed April 23, 1923

Inventor:
Albert Wagner,

By Chas. E. Rindge
Atty.

Patented Oct. 16, 1923.

UNITED STATES PATENT OFFICE.

ALBERT WAGNER, OF CINCINNATI, OHIO, ASSIGNOR TO THE WEMB COMPANY, OF CINCINNATI, OHIO, A CORPORATION OF OHIO.

AUXILIARY AIR VALVE FOR INTERNAL-COMBUSTION ENGINES.

Application filed April 23, 1923. Serial No. 634,095.

To all whom it may concern:

Be it known that I, ALBERT WAGNER, of Cincinnati, in the county of Hamilton and State of Ohio, a citizen of the United States, have invented certain new and useful Improvements in Auxiliary Air Valves for Internal-Combustion Engines, of which the following is a specification.

This invention is an auxiliary air valve, of the type disclosed in application filed by me October 9, 1922, Serial No. 593,294, for admitting air between the carbureter and the intake manifold of an internal combustion engine to be mixed with the fuel from the carbureter, the objects of the present invention being to simplify the construction, reduce the cost of production, and increase the efficiency of the device.

The invention is illustrated in the accompanying drawing and will be hereinafter fully set forth.

In the drawing, Fig. 1 is a side elevation and the trunk of an intake manifold having my improved device associated therewith.

Figs. 2 and 3 are elevations showing opposite sides of the improved device,

Fig. 4 is a section on the line 4—4 of Fig. 3,

Fig. 5 is a longitudinal section on the line 5—5 of Figure 4,

Fig. 6 is a similar view on the line 6—6 of Fig. 4,

Fig. 7 is a detail section on the line 7—7 of Fig. 5.

The carbureter 1 is illustrated in a conventional manner and may be of any known or preferred construction. It is provided at 2 with a throttle valve controlled by a lever 3 which is actuated by a throttle rod, not shown. The fuel flowing from the carbureter is delivered into the trunk 4 of the intake manifold and thence passes into the engine cylinders. Between the carbureter outlet and the trunk 4 I interpose a flat-sided substantially elliptical body 5 having a transverse opening 6 therethrough to align with the said outlet and the bore of the trunk, and bolts 7 are inserted through the said body and through flanges or lugs on the carbureter and the trunk to secure the body firmly in place, gaskets 8 being disposed between the sides of the body 5 and the said flanges or lugs to prevent leakage.

A lining ring 9 is fitted in the opening 6 and secured in place by brazing or in

any other preferred or convenient manner. The ring 9 is provided with two annular series of perforations or ports 10 and 11 which register, respectively, with the annular grooves 12 and 13 in the wall of the opening 6, the groove 12 being narrower than the groove 13 and the perforations 10 being smaller than the perforations 11.

At one end of the body is a vertically disposed cylinder 14 and at the lower end of said cylinder is a circular enlargement or projection 15, one side of the enlargement being constructed to receive and partly support the nipple 16 with which is engaged

the end of an air supply pipe, the illustration of which is not necessary to an understanding of my invention. A transverse spindle 17 extends through the enlargement 15 centrally thereof and is rotatable therein while arranged eccentrically in the enlargement on different diameters of the same, are ports 18 and 19 of unequal capacities.

A passage or channel 20 extends through the body 5 from the port 19 to the annular groove 12 and establishes communication between said port and groove, while a short passage 21 leads from the port 18 into the hollow interior of the cylinder 14 and a passage 22 leads from the cylinder to the groove 13 whereby communication between the port 18 and the groove 13 is established.

A ball valve 23 seats in the upper end of the passage 21 and is yieldably held to its seat by a spring 24 bearing upon the valve, as shown. A plug 25 is threaded into the upper end of the cylinder 14 and bears upon the upper end of the spring 24 to regulate the tension of the same, a locking washer 26 being mounted on said plug 25 and bearing upon the top of the cylinder to lock the plug in a set position. The ports 18 and 19 open through one side of the enlargement 15 and a disk cut-off valve 27 controls the flow through said ports, said disk valve being carried by the adjacent end of the spindle 17 and lying close against the face of the member 15. Notches 28 and 29 are formed in the edge of the disk valve to uncover the ports 18 and 19 respectively, both ports being covered normally by the portion of the disk between the notches, as shown in Fig. 3. The notches are at diametrically opposite points of the disk but the ports are out of alignment so

that, in the operation of the device, the

notch 29 will uncover the port 19 but the port 18 will remain covered until additional or further movement is imparted to the disk.

Upon the end of the spindle 17 remote 5 from the disk valve is secured a crank 30 and a link 31 connects said crank with the lower end of a trip lever 32 which is pivotally mounted between lugs 33 on the body 5 at the end of the same remote from the cylinder 14. The trip lever has its upper end arranged in the path of a trip on the throttle rod to be actuated in the manner set forth in my hereinbefore identified application. A coiled spring 34 is arranged 10 around the projecting end portion of the spindle 17 and has one end secured to the body 5 and its opposite end attached to the link 31 or the crank 30 so that it tends constantly to hold the disk valve in the position, shown in Fig. 3, in which the ports 18 and 19 are both covered and the inflow of air is cut off.

If the engine be running idle or at a very 25 low speed, the ports 18 and 19 will be closed as shown. When the throttle is opened to admit more fuel and increase the speed of the engine, the lever 32 will be rocked and its movement is transmitted through the link 31 to the crank 30, the spindle 17 and the valve 30 27 being, consequently, rocked so that the notches 28 and 29 are moved toward the ports 18 and 19. As the movement continues, the port 19 will be uncovered and, subsequently, the port 18 will be uncovered. 35 When the port 19 is uncovered air will at once flow through the same and thence through the passage 20 into the groove 12, escaping through the perforations 10 in small streams of high velocity which will 40 penetrate the mixture flowing from the carbureter. When the port 18 is uncovered and the engine speed increases, however, the suction and air pressure will eventually overcome the force of the spring 24 whereupon the valve 23 will be unseated and air 45 will flow through the passage 22 to the groove 13 and escape through the perforations 11 to penetrate the charge. As the engine speed decreases, the valve 23 will be seated but the ports 18 and 19 will remain open until the throttle rod is shifted in the proper direction and to the proper extent to permit the disk 27 to return to closed position.

50 My improved device is very simple and may be produced at a very low cost. By its use, mileage per gallon of fuel is increased and the engine will run more smoothly and with greater speed and power than heretofore owing to the additional air supply which is discharged at high velocity into the mixture supplied by the carbureter. The inner valve 23 is brought into action only after the port 19 is fully opened, and supplies needed additional air as the 55 speed increases.

Having thus fully described my invention, what I claim as new and desire to secure by Letters Patent of the United States is:—

1. A device of the character described 70 adapted to be placed between a carbureter and an internal combustion engine comprising a body having an opening to register with the outlet of the carbureter, said body having a plurality of passages to admit air 75 to said opening, said passages having inlet ports in a side of the body, a cut-off valve rotatably mounted on the body and fitting close to the side of the same, said valve consisting of a disk normally covering both 80 said inlet ports and provided with diametrically opposite notches whereby rotation of the disk will successively uncover both said ports, and a normally closed valve in one of the passages operable to open after 85 both inlet ports have been uncovered.

2. A device of the character described adapted to be placed between a carbureter and an internal combustion engine comprising 90 a body having an opening to register with the outlet of the carbureter, said body having a plurality of passages to admit air to said opening, said passages having inlet ports in a side of the body, a cut-off valve 95 rotatably mounted on the body and fitting close to the side of the same, said valve consisting of a disk normally covering both said inlet ports and provided with diametrically opposite notches whereby rotation of the disk will successively uncover 100 both said ports, a ball valve seating at an intermediate point of one of the passages to close the same, and a spring bearing upon said ball valve and holding it seated until after the mechanical valve has been opened. 105

3. A device of the character described adapted to be placed between a carbureter and an internal combustion engine comprising 110 a body having an opening to register with the outlet of the carbureter, said body having a plurality of passages to admit air to said opening, said passages having inlet ports in a side of the body at one end thereof, a rotatable spindle extending 115 through said end of the body, a cut-off valve carried by said spindle to normally close both said inlet ports and constructed to open them successively upon rotation, a crank upon said spindle, a lever mounted upon the opposite end of the body and adapted to be actuated by the throttling mechanism of the carbureter, a link connecting said lever and the crank, and yieldable means acting on the crank for holding 120 the cut-off valve normally in closed 125 position.

In testimony whereof I hereunto affix my signature.

ALBERT WAGNER.
